PORTABLE BAR CABINET

Jeff Anderson, 843 E. Jefferson Ave., Los Angeles, Calif.

Filed Aug. 21, 1961, Ser. No. 66,434

Term of patent 14 years

(Cl. D33—19)

FIG 1

FIG 5

FIG. 1 is a top plan view of a portable bar cabinet, showing my new design.

FIG. 2 is a front elevational view thereof.

FIG. 3 is a side elevational view of the portable bar cabinet.

FIG. 4 is a sectional view taken on line 2—2 of FIG. 2, and

FIG. 5 is a perspective view of the portable bar cabinet shown in open position.

I claim:

The ornamental design for a portable bar cabinet, substantially as shown.
